 1 Claim. (Cl. 165—164)

This invention relates essentially to heat exchangers and notably to heat exchangers of the type comprising a nest of parallel longitudinally aligned tubes adapted for effecting heat transfer between a heat exchanging medium passing through the interior of said tubes and an external fluid flowing in a generally longitudinal direction through said nest along the external surfaces of said tubes.

A primary object of this invention is to promote the efficiency of a heat exchanger of the type referred to by creating a secondary transverse movement of the external fluid, namely, by introducing between adjacent tubes helically wound strip means adapted to impart a gyratory motion to said fluid.

It is another object of this invention to promote the efficiency of a heat exchanger of the type referred to by forming on the tube integral fin means extending substantially transversely thereof, with a view to increase the area of said tubes in contact with said fluid, and to promote and maintain said gyratory motion.

It is a further object of this invention to provide a heat exchanger of the type referred to, having a compact and reliable structure.

The heat exchanger according to this invention comprises a nest of longitudinally extending parallel tubes adapted for the passage therethrough of the heat exchange medium to effect heat transfer between said medium and an external fluid circulating in a generally longitudinal direction through said nest along the external surfaces of said tubes. The outer surfaces of said tubes are peripherally grooved to form on said surfaces integral fin means extending substantially transversely of said tubes. The tubes are arranged in an array of rows and columns such that the axes of said tubes respectively define a regular triangular mesh pattern in which a tube in any one row forms a regular triangle with two adjacent tubes, at least one of which lies in an adjacent row. On the outer surface of selected tubes are provided helically wound strip means, while the remainder of the tubes are bare or plain. The tubes with the strip means are selected such that each plain tube is surrounded by tubes with strip means thereon and in each row there is alternately disposed a plain tube and two tubes with strip means thereon. Moreover, the strip means are helically wound in opposite directions on adjacent tubes, each strip means contacting the outer surface of an adjacent tube such that each tube with strip means thereon is disposed between a bare tube and a tube with strip means thereon which is wound in an opposite direction, while each bare tube is disposed between two tubes with strip means thereon which are wound in opposite directions.

Further objects and features of the invention will become apparent from the following description taken with reference to the attached drawing in which:

FIGURE 1 illustrates diagrammatically in cross section one portion of a nest of heat exchange tubes according to the invention,

FIGURE 2 is a diagrammatical side elevational view showing one row of tubes as taken along arrows II—II in FIG. 1,

FIGURE 3 is a detail view, with parts shown in axial section, of one end of the nest illustrated in FIGS. 1 and 2, and

2

FIGURE 4 is a cross-section taken along line IV—IV of FIG. 3.

According to a preferred embodiment of the invention as illustrated in the drawing, a heat exchanger comprises 5 a triangular mesh nest. In this respect the nest is considered to be comprised of bare tubes 10 arranged in an array of rows and columns such that the axes of the tubes 10 respectively define a regular triangular mesh pattern in which a tube in any row forms a regular triangle with 10 two adjacent tubes, at least one of which lies in an adjacent row. A fluid medium circulates externally of the tubes in a generally longitudinal direction, for example from top to bottom, and contacts the walls of the tubes which are formed with relatively shallow peripheral 15 grooves extending transversely. In order to improve the efficiency of the heat exchanger a rotary motion is imparted to the circulating fluid in each stream formed between adjacent tubes 10 by interposing between the tubes further tubes similar to those of tubes 10 but having 20 wound and secured thereon a flat, spiral-forming strip adapted to impart a gyratory motion to the fluid. In the embodiment illustrated in FIGURE 1 there is interposed between adjacent tubes 10 tube 11 similar to tubes 10 but having wound and secured thereon, for example 25 by spot welding, a flat forming strip 12. This strip 12 extends preferably normally to the surface of the tube on which it is wound and secured. From FIGURE 1, it will be seen that the width of strip 12 is such that its outer edge engages the wall of the tubes 10. In the mesh consisting of the two tubes 10 located respectively in the lower left-hand corner and in the center of FIG. 1 and 30 of the tube 10 of which only one half is visible in the middle of the lower border of the figure, there is disposed another tube 14 having wound thereon a spiral-forming strip 15 of which the pitch is opposite to that of spiral 35 12. With this arrangement, the fluid streams circulating from top to bottom will obviously be forced along a transverse gyratory path shown by the arrows of FIGURE 1 and 2. Since the pitches of the spiral strips have 40 opposite directions on adjacent tubes such as 11 and 14 or 14 and 16, it is possible as shown in FIG. 2 to imbricate the strips associated with these tubes and to bring the strips in contact with the outer walls of the adjacent tubes, whether these tubes themselves are provided with 45 strips or not. Thus, a compact tubular nest is obtained, wherein the tubes bear against one another and are thus protected against vibration. As shown in FIGURE 1, the number and cross-sectional area of vertical by-pass passages through which the fluid might flow directly without producing the necessary heat exchanges are relatively 50 low.

The heat exchanger structure as hereinabove described could be considered as well in terms of an array of tubes. Indeed, any one of the tubes shown in FIG. 1 pertains 55 to three angularly equidistant rows of tubes, such as the row along line II—II shown in elevational view in FIG. 2. In each row a bare tube, such as tube 10, is located between two tubes such as tubes 11—17, 14, 19 or 16—18, provided with fin-like strip means wound helically thereon according to opposite pitches respectively. Similarly, tube 11 is disposed between a bare tube 10 and a tube provided with opposite pitch helical strip means, such as tubes 14 or 18, according to the row being considered.

The heat exchanger structure as shown could be further described by considering that any one of the tubes shown in FIG. 1 is surrounded by six adjacent tubes, and that these seven tubes constitute a unit mesh of the heat exchanger nest.

From a mere consideration of the figure, it will clearly appear that in each such mesh, the central tube, whether it is bare or provided with left-hand or right-hand heli-

cal strip means, is surrounded by six tubes in a particular arrangement. By way of example, the bare tube 10 located centrally of FIG. 1 is surrounded by tubes 11, 16 and 19, provided with left-hand wound helical strip means 12 and by tubes 14, 17 and 18 provided with right-hand wound helical strip means 15, whereas each tube with a strip means thereon is surrounded by alternating bare tubes and tubes with strip means thereon in which the latter are all wound in opposite direction with respect to the strip means on the central tube.

FIGURES 3 and 4 illustrate the manner in which the seven tubes 10, 11, 14 and 16-19 constituting a central hexagonal mesh in FIG. 1 are interconnected at their upper and/or lower ends in the case of a vertical heat exchanger, the tube end portions being left plain after the formation of the fins, splines, ribs, grooves or low-pitch threads therein. The central tube 10 has six circular ports formed therein, these ports being disposed as shown by diametrically opposite pairs in three superposed planes intersecting the tube axis at 60-degree intervals, the necks of the bent ends of tubes 11, 14, 16, 17, 18 and 19 being welded on the wall of the central tube 10, as shown.

As shown in FIGS. 1 and 2 the main portion of each tube has fitted therein a cylindrical core such as 10a, 11a, 17a, etc. in a cylindrical or tubular core such as 11a, 10a, 17a closed at top and bottom by a streamlined, water-tight or nearly water-tight tip portion as shown at 11b, 16b and 17b in FIG. 3. Thus, the cross-sectional area of the annular space formed between the tubes 11 and 11a, 10 and 10a, 17 and 17a corresponds substantially to that of the tapered and bent end portions of these tubes which connect the latter to the central tube 10.

With this arrangement the six mesh-forming tubes can be connected to the central tube by means of slightly tapered end portions without restricting the cross-sectional area available for the passage of the inner fluid. This arrangement is particularly valuable in the case of nuclear reactors wherein the number of welds should be as small as possible.

For properly wedging the central tubular core in the tubes and improving the heat exchange, it is advantageous to provide a tube, braid or spiral-wound strip of a width of thickness substantially equal to the radial dimension of the annular space left between the outer surface of the core and the inner surface of the tube. The provision of this spiral or coil-wound distance-piece ensures a proper stabilization in case of a vertical heat exchanger in which the water reheat followed by the water vaporization and finally the superheating of the steam thus produced are accomplished sequentially at different levels. By providing a non-sealed central tubular core, that is, a tubular core more or less open at its ends, this specific operation is improved since it is possible to constitute within this core a make-up reserve of water which, during the operation of the heat exchanger, has a temperature increasing gradually from bottom to top up to vaporization temperature.

The construction of the device just described is particularly convenient if tubes having end portions are used

with a view to form the tapered tips mentioned hereinabove to permit the proper connection of the tube constituting one mesh with the main or central tube.

FIGURE 4 illustrates by way of example this hexagonal distribution of the six tubes 11, 14, 16, 17, 18 and 19 about the central tube 10.

Of course, this invention is also concerned with a tubular nest having a square pattern.

Although the present invention has been described in conjunction with a preferred embodiment, it is to be understood that modifications and variations may be resorted to without departing from the spirit and scope of the invention, as those skilled in the art will readily understand. Such modifications and variations are considered to be within the purview and scope of the invention if defined by the appended claim.

What I claim is:

A heat exchanger comprising a plurality of longitudinally extending parallel tubes adapted for the passage therethrough of a heat exchange medium, said tubes being arranged in an array of rows and columns such that the axes of said tubes in any one row forms a regular triangle with two adjacent tubes at least one of which lies in an adjacent row, said tubes being adapted for the passage along the external surfaces thereof of a second heat exchange medium, said tubes having peripheral transverse grooves in the outer surfaces thereof, said grooves extending substantially perpendicular to the longitudinal direction of the tubes, helically wound strip means on the outer surface of selected tubes, the remainder being plain, said tubes with the strip means being selected such that each plain tube is surrounded by tubes with strip means thereon and in each row there are alternately disposed a plain tube and two tubes with strip means thereon, said strip means being helically wound in opposite directions on adjacent tubes each strip means contacting the outer surface of an adjacent tube, such that each tube with strip means thereon is disposed between a plain tube and a tube with strip means thereon which is wound in an opposite direction, while each plain tube is disposed between two tubes with strip means thereon which are wound in opposite directions.
